[57] CLAIM

The ornamental design for an aircraft, substantially as shown and described.

DESCRIPTION

FIG. 1 is a top plan view of an aircraft showing my new design;

FIG. 2 is an elevational view of one side of said aircraft, the elevational view of the other side being substantially a mirror image thereof;

FIG. 3 is a bottom plan view of said aircraft;

FIG. 4 is an elevational view of the front of said aircraft;

FIG. 5 is an elevational view of the rear of said aircraft.

*Fig. 1**Fig. 2**Fig. 3**Fig. 4**Fig. 5*
